RECEPTACLE FOR A FOOD JAR

Kenenth W. Dennis, Oak Lawn, Ill., assignor to Libby, McNeill & Libby, Chicago, Ill., a corporation of Maine

Application March 19, 1959, Serial No. 55,064

Term of patent 14 years

(Cl. D44—10)

Fig. 1.

Fig. 2.

Fig. 3.

Fig. 4.

Fig. 5.

Figure 1 is a perspective view of a receptacle for a food jar, showing my new design;

Figure 2 is a side elevational view thereof;

Figure 3 is a plan view thereof;

Figure 4 is a bottom view thereof; and

Figure 5 is a vertical cross-sectional view thereof with the view being taken along the line 5—5 of Figure 3 looking in the direction indicated by the arrows.

I claim:

The ornamental design for a receptacle for a food jar, as shown.
